CARL HUGO THORNBLADE, OF SEATTLE, WASHINGTON, ASSIGNOR TO PACIFIC ELECTRIC WELDER & MANUFACTURING CO., OF SEATTLE, WASHINGTON, A CORPORATION OF WASHINGTON.

METAL FISH-BASKET.

1,252,740.

Specification of Letters Patent.

Patented Jan. 8, 1918.

Application filed January 10, 1916. Serial No. 71,345.

To all whom it may concern:

Be it known that I, CARL HUGO THORNBLADE, a citizen of the United States, and resident of the city of Seattle, county of 5 King, State of Washington, have invented certain new and useful Improvements in Metal Fish-Baskets, of which the following is a specification.

My invention relates to an improvement 10 in baskets, constructed of metallic bars, such, for instance, as are used in the handling and treating of fish.

The object of my invention is to construct a basket along these lines in such manner 15 that it will have superior strength and durability, as compared with baskets of this type constructed in the ordinary manner. The particular features of which my invention consists will be hereinafter set forth in the 20 specification, and particularly defined in the claims.

In the accompanying drawings I have shown my invention in the form which is now most preferred by me.

25 Figure 1 shows in perspective a basket constructed in accordance with my invention.

Fig. 2 is a transverse sectional elevation of the same basket.

30 The basket here shown is one which is composed of a series of flat bars of iron, bent so that each bar extends across the bottom of the basket and to each opposite side. Two sets of such bars are used, these 35 extending at right angles and together form a grill work. Each bar has a section which is comprised within the bottom of the basket, and two end sections which are comprised within the sides of the basket. The 40 bars 1 in the basket illustrated extend across the shorter dimension of the basket, while the bars 2 extend the longer dimension of the basket.

There is no interweaving of these bars 45 but they are secured to each other in proper position by welding at their point of crossing, this welding being most economically and perfectly performed by the use of an electric welder.

50 Horizontal bars 3 extend about the sides of the basket, and are similarly joined at their meeting ends and at their point of intersection with the bars 1 and 2 by weld-

ing. Each of the bars 1 and 2 at its upper end is offset as shown at 12, this offset being 55 sufficient to form a shoulder upon which rests the lower edge of the binding bar 4, which extends around the brim of the basket. This binding bar is also secured to the bars 1 and 2 by being electrically welded thereto. 60

As the baskets when in use are stacked one upon another, sometimes to a considerable height and this while filled with fish, the weight carried by the sides of the basket 65 sometimes become very considerable. The use of the shoulder 12 strengthens the basket by transferring some of this weight through the contact at this point, rather than carrying it only through the welded joint, in consequence the basket is stronger because of 70 this feature, and better able to support heavy weights without loosening the welded joints.

The bars 1 which extend across the basket 75 in the direction of its shorter dimension are all entirely within the bars to which they are secured, with the exception of the binding bar 4, in such cases where this binding bar is placed at the inner side of the vertical sections 80 of the outer bars. It is of course understood that the binding bar 4 might be placed without the vertical sections of these bars if desired, in which case the offset 12 would be in opposite direction from that 85 shown. The bars 2 which extend lengthwise the basket, are outside of or across the transverse bars 1, and inside of the horizontal side bars 3. A basket of this construction may be made more cheaply than when 90 the basket is riveted, and at the same time the joints will be stronger and less liable to rust, furthermore baskets for handling fish are subjected to the action of salt, which gets under the heads of the rivets and 95 eventually loosens the joint. This could not act to loosen a welded joint.

What I claim as my invention is:

1. A basket composed of bars forming a metallic grill, the vertical bars of the sides 100 being bent to form laterally off-set sections at their ends, and a binding bar extending about the brim with its lower edge bearing upon the shoulders formed by said offsets, the crossing points of the bars being secured 105 by welding.

2. A basket composed of bars forming a metallic grill, the vertical bars at the sides being bent to form laterally offset sections at their ends, a binding bar extending about 5 the brim with its lower edge bearing upon the shoulders formed by said offsets, and the horizontal bars at the sides being outside of

the vertical bars throughout the entire periphery, the crossing points of the bars being secured by welding.

Signed at Seattle, Washington this 21st day of December 1915.

CARL HUGO THORNBLADE.
